UNITED STATES PATENT OFFICE

KYLE E. STANT, OF CONNERSVILLE, INDIANA, ASSIGNOR TO THE STANT MACHINE COMPANY, OF CONNERSVILLE, INDIANA, A CORPORATION OF INDIANA

RADIATOR CAP

Application filed March 23, 1929. Serial No. 349,471.

This invention relates to closures for receptacles and particularly to closures for radiator caps.

It is an object of this invention to provide a radiator cap consisting of a non-rotatable member carried by the receptacle and a non-rotatable member carried by the first member for forming a closure.

It is also an object of this invention to provide, in connection with a radiator cap or other closures for vessels, a resilient diaphragm member adapted to cooperate with the gasket to form a close fitting relation between the receptacle and the closure and to provide a securely effective means for locking the lid to the receptacle in such a way that it cannot be easily removed or unlocked so that the contents of the receptacle will be wasted.

It is a further object of this invention to provide a lid or closure for receptacles in which the lid is easily supported on the upper end of the spout of the receptacle and is held in locked engagement therewith by means of a sliding latch operated in locking position by a flat spring and released by means of a lever that is substantially concealed and not readily operated except when it is desired to release the latch to remove the lid.

For this purpose the lever is mainly concealed and has exposed to contact only a small part for the purpose of operating the lever and releasing the latch.

For the purpose of illustration there is shown a preferred embodiment of this invention in the accompanying drawings.

Referring to the drawings:

Figure 1 is a longitudinal vertical sectional view of this invention showing the lid in closed position.

Figure 2 is a view similar to Figure 1 with the latch released and the lid partly open.

Figure 3 is a section on the line 3-3 of Figure 2.

Figure 4 is a side view of the collar with the lid open. This view also shows a modified form of attachment by which the collar is attached to the filler spout of the container.

Figure 5 is a top plan view of the collar shown in Figure 4.

Figure 6 is an inside elevation of the lid.

This device is adapted to be used in connection with filler spouts or receptacles, but it is more particularly adapted for use in connection with filler spouts on radiators.

For the purpose of attaching the device to the filler spout of a receptacle or a radiator there is provided an annular collar 1, which has the usual threads 2 by which the collar is attached to the filler spout. The general appearance of the filler spout is oval in shape, and has from the outer periphery thereof a downward extending flange 3 and an upward extending flange 4, which provide an oval shaped seat. Within the seat and on the upper surface of the collar there is provided an annular groove 5 which receives a gasket 6. This gasket may be composed of any suitable material but is preferably composed of some fibrous material that is adapted to resist the action of the fluid within the container or radiator, and to retain its elasticity for the purpose of forming a closure with the cooperating part of the lid.

To one side of the collar there are ear members 7. These ear members are two in number, and arranged in spaced relation to each other to provide one element of a hinge member. Opposite the ears 7 there is provided a latch receiving slot 8, which is adapted to receive a latch member carried by the lid. The lid is indicated by the numeral 9, and is of a general oval shape, and has a lug 10 on one side thereof for the purpose of cooperating with the ears 7 to form the hinge connection between the collar and the lid.

Passing through these ears and this lug is a hole for the reception of a spindle 11 about which the parts turn for the purpose of opening and closing the lid. On the outer periphery of the circular part of the lid there are arranged two substantially semi-circular ribs 12. These ribs do not come together at their ends but leave a space therebetween for the passage of the latch member. Fitting within these semicircular ribs is a flexible diaphragm member 14 carried by the central thimble member 13 extending from the inner central part of the lid.

For the purpose of locking the lid in closed

100

relation to the collar there is provided a latch 15. This latch has a large central slot 16 and two small slots 17, one near each end thereof. The central slot is provided in the latch for the purpose of receiving the central thimble 13 so that at this part the latch member substantially straddles the thimble 13 and moves back and forth with the thimble within the large slot.

10 The purpose of the small slots is to receive the studs 18. On the ends of the studs 18 there are reduced parts 19 which fit within the slot 17 to guide the latch member, and for the purpose of holding the latch member in engagement with the studs there is placed over the ends of the reduced parts of the studs, washers 20.

20 For the purpose of holding these washers in place the outer ends of the studs are turned over, as indicated by the numeral 21, in engagement with the faces of the washers so that the washers cannot be removed from the studs. The front end of the latch member 15 is indicated by the numeral 22 and is adapted 25 to engage in the slot 8 of the collar for the purpose of holding the lid in locking engagement with the collar. The rear end of the latch is indicated by the numeral 23 and has therein a hole 24 to receive a lug 25 on the inner end of a lever 26. The lever 26 is pivoted at the point indicated by the numeral 27, about which it turns in the operation of the latch.

25 For the purpose of operating the lever to release the latch there is provided serrations 28 on the outer end of the lever to be engaged by the hand of the person who operates the lever to release the latch. For the purpose of holding the latch in position to engage the slot in the collar there is provided a spring 29 which is attached to the lid at points indicated by the numeral 30. Thus the spring is attached at each end to the lid, while the central part of the spring 40 engages a stud 31 extending upward from the latch member.

Instead of the screw thread connection, as indicated by Figures 1 and 2, the collar may be fastened to the filler spout of a receptacle by means of the device shown in Figure 4. In this figure there are shown two projections 32, which extend downward from the collar and are adapted to fit within the spout of the receptacle. For the purpose of fastening the collar to the spout of the receptacle there are provided screws 33, which have on their outer ends a cone-shaped point for the purpose of engaging a cooperating part on the upper edge of the filler spout.

60 It is obvious from the foregoing description that applicant has provided a simple and inexpensive and easily operated cap, adapted to be used in connection with filler spouts of receptacles, and particularly radiator caps.

65 There has been provided a cap with a lid

adapted to be securely held in concealing relation to the upper part of the filler spout, and one that cannot be easily removed without it being the purpose to remove the lid so that access may be had to the receptacle.

I desire to comprehend within my invention such modifications as may be clearly embraced within my claims and the scope of my invention.

Having thus fully described my invention, what I claim is new and desire to secure by Letters Patent, is:

70 1. In a radiator cap in combination with a collar, a lid having a sleeve therein, a slidably mounted latch member having a slot 80 therein for the sleeve, a sealing means on said sleeve, and means to operate the latch member to lock the lid and sealing means in engagement with the collar.

2. In a radiator cap in combination with a collar, having an annular gasket thereon, a lid having a sleeve therein, a slidably mounted slotted latch member on said lid, with the sleeve in said slot, a resilient sealing means on said sleeve, and means to operate the latch member to lock the lid and sealing means in engagement with the collar and the gasket.

25 3. In a radiator cap in combination with a collar having a slot therein, a lid pivotally mounted on said collar, said lid having a 90 guide member thereon, a sliding latch supported and guided by said guide member, and means to force said latch into said slot to lock the lid in engagement with the collar.

4. In a radiator cap in combination with a collar having a latch receiving slot therein, a lid pivotally mounted on said collar, a plurality of guides on said lid, a latch slidably supported and guided by said guides, means on the lid to hold the latch in engagement with the slot when the lid is closed, and manually operable means to release said latch.

100 5. In a radiator cap in combination with a collar having a latch receiving slot therein, a lid pivotally mounted on said collar, a plurality of guides and a sleeve projecting from said lid, a latch having slots to receive said guides and sleeve to be guided and supported thereby, means on the lid to force the latch into engagement with said slot when the lid 110 is closed, and means to release said latch.

115 6. In a radiator cap in combination with a collar having a latch receiving slot therein, a lid pivotally mounted on said collar, a plurality of guides and a sleeve projecting from said lid, a sliding latch having slots to receive said guides and sleeve to be guided and supported thereby, means on the lid to force the latch into engagement with said slot when the lid is closed, and means to release said latch.

120 7. In a radiator cap in combination with a collar having a latch receiving slot therein, a lid pivotally mounted on said collar, a plurality of guides and a sleeve projecting from 130

said lid, a latch having slots to receive said guides and sleeve to be guided and supported thereby, lever means on the lid to force the latch into engagement with said slot when the lid is closed, and means to release said latch.

8. In a radiator cap in combination with a collar having a latch receiving slot therein, a lid pivotally mounted on said collar, a plurality of guides and a sleeve projecting from said lid, a latch having slots to receive said guides and sleeve to be guided and supported thereby, means on the lid to force the latch into engagement with said slot when the lid is closed, and lever means to release said latch.

9. In a radiator cap in combination with a collar having a slot therein, a lid having a slot therein pivotally connected to said collar, a spring operated latch having a plurality of slots therein adapted to engage the first named slot to hold the lid locked to the collar, means on said lid to engage part of the slots on the latch to support and guide said latch, and a lever mounted in the second named slot and in engagement with the latch to release the latch from engagement with said first slot.

10. In a radiator cap in combination with a collar having a latch receiving slot, a lid hinged to said collar, a pair of latch supports on said lid, a slidable latch having a pair of slots to receive said supports, and a lever on said lid in engagement with said latch to release said latch from the collar slot.

11. In a radiator cap in combination with a collar having a latch receiving slot therein, a lid hinged to said collar, a latch slidably mounted in said lid and adapted to engage in said slot to lock the lid on the collar, and a lever on said lid and in engagement with the latch to release the latch.

12. In a radiator cap in combination with a collar having a latch receiving slot therein, a lid hinged to said collar, a spring pressed latch slidably mounted in said lid and adapted to engage in said slot to lock the lid on the collar, and a lever on said lid and in engagement with the latch to release the latch.

13. In a radiator cap in combination with a collar having a latch receiving slot therein, a lid hinged to said collar and having a lever receiving slot therein, a latch slidably mounted in said lid and adapted to engage said first named slot to lock the lid on the collar, and a lever mounted in said second named slot and in engagement with the latch to release the latch.

14. In a radiator cap in combination with a collar having a latch receiving slot therein, a lid hinged to said collar and having a lever receiving slot therein, a spring pressed latch slidably mounted in said lid and adapted to engage said first named slot to lock the

lid on the collar, and a lever mounted in said second named slot and in engagement with the latch to release the latch.

In testimony whereof, I affix my signature.
